UNITED STATES PATENT OFFICE.

ADOLPH L. NELSON, OF DETROIT, MICHIGAN, ASSIGNOR TO BOHN ALUMINUM & BRASS CORPORATION, OF DETROIT, MICHIGAN.

FURNACE.

Application filed June 15, 1925. Serial No. 37,314.

The invention relates to furnaces and refers more particularly to holding furnaces having pots containing molten metal which is removed by ladles.

5 Heretofore holding furnaces have been constructed in such a manner that when the flame below the pot has eaten away either or both of the portions of the wall and pot constituting the connection or joint 10 between the parts, the foreign material such as scale from the wall and the pot has been blown into the pot and the molten metal contained therein, thereby damaging the latter. With my invention this foreign material 15 is deflected away from the pot so that it cannot enter the molten metal. Furthermore this foreign material is directed downwardly at the outside of the wall so that it will cause no injury to the workman. With 20 these as well as other objects in view the invention resides in the novel features of construction and combinations and arrangements of parts as more fully hereinafter set forth.

25 In the drawings:—

Figure 1 is a plan view of a holding furnace embodying my invention;

Figure 2 is a transverse section therethrough;

30 Figure 3 is a similar view showing portions of the wall and pot eaten away.

1 is the pot of the holding furnace containing the molten metal and having an open upper end. 2 is the wall for supporting the pot with its bottom above the floor so that the flame has free play with the surface of the pot confined within the wall to maintain the molten metal at the proper temperature. The wall is annular and is 35 preferably formed of bricks with the annular metallic ring 3 at its top upon which rests the annular flange 4 at the upper edge of and integral with the pot, the joint between this ring and flange being normally closed.

40 45 5 is a metallic ring which rests directly upon the flange 4 and is preferably provided with the depending cylindrical flange 6 for positioning the ring upon the pot. This ring extends outwardly over the ring 3 of 50 the furnace wall and is spaced thereabove

and terminates in the downwardly extending cylindrical flange 7, which is located outwardly beyond the outer side of the wall and extends below the ring thereof. With this arrangement, the metallic ring 5 rests 55 at all times upon the pot so that in the event that the flame eats away the material of the wall ring or pot flange normally forming the closed joint and escapes carrying with it the foreign material such as scale of the wall 60 or pot, this foreign material is carried outwardly over the wall and deflected downwardly at the outside thereof so that it cannot enter the pot and the molten metal therein and will not cause injury to the 65 workman.

What I claim as my invention is:

1. In a holding furnace, the combination with an annular wall, of a pot having an annular flange at its upper edge resting upon said wall and forming a joint therewith, and a ring supported upon said annular flange and extending outwardly therebeyond for deflecting foreign material which might pass outwardly through said joint away 75 from said pot.

2. In a holding furnace, the combination with an annular wall, of a pot having at its upper edge an annular flange resting upon said wall and normally forming a closed 80 joint therewith, and a ring supported upon said annular flange and extending over said wall and provided with a depending flange outside of said wall for deflecting foreign material which might pass outwardly 85 through said joint away from said pot and downwardly outside of said wall.

3. In a holding furnace, the combination with an annular wall, of a pot having at its upper edge an annular flange resting upon said wall and normally forming a closed 90 joint therewith, and a ring upon said annular flange and provided with positioning means engageable with the pot, said ring extending adjacent to said joint for 95 deflecting foreign material which might pass outwardly through said joint away from said pot.

In testimony whereof I affix my signature.
ADOLPH L. NELSON.
